DETACHABLE STATION WAGON TOP

Arthur J. Camp, North Hollywood, Calif., assignor to Joel Patrick, Incorporated, Sherman Oaks, Calif., a corporation of California

Filed Dec. 27, 1966, Ser. No. 5,191

Term of patent 14 years

(Cl. D14—3)

FIG. 1 is a side elevational view of a detachable station wagon top showing my new design.

FIG. 2 is a partial plan view and partial sectional view as taken on the plane of line 2—2 of FIG. 1.

FIG. 3 is a rear perspective view, with a portion of the rear window broken away, to show detail therebeyond.

FIG. 4 is a front perspective view.

I claim:

The ornamental design for a detachable station wagon top, substantially as shown.
